UNITED STATES PATENT OFFICE.

LOUIS H. MCKEE, OF TRENTON, NEW JERSEY.

DESIGN FOR A SCHOOL-DESK.

58,247.

Specification for Design. Patented June 28, 1921.

Application filed December 8, 1920. Serial No. 429,288. Term of patent 14 years.

To all whom it may concern:

Be it known that I, LOUIS H. MCKEE, a citizen of the United States, residing at Trenton, in the county of Mercer, State of New Jersey, have invented a new, original, and ornamental Design for School-Desks, of which the following is a specification, reference being had to the accompanying drawing, forming part thereof.

The figure is a side elevation of a school desk showing my new design.

I claim:—

The ornamental design for a school desk, as shown.

LOUIS H. MCKEE.
